UNITED STATES PATENT OFFICE.

HARRY KRAUTBLATT, OF CHICAGO, ILLINOIS, ASSIGNOR OF ONE-THIRD TO FRANK S. RUSSELL AND ONE-THIRD TO STEPHAN SESTAK, BOTH OF CHICAGO, ILLINOIS.

AUTOMATIC INGOT FEEDER.

Application filed April 11, 1921. Serial No. 460,570.

To all whom it may concern:

Be it known that I, HARRY KRAUTBLATT, a citizen of the United States, residing at Chicago, in the county of Cook and State of Illinois, have invented certain new and useful Improvements in Automatic Ingot Feeders, of which the following is a description.

My invention relates to improvements in ingot feeders and particularly to a device which will automatically feed ingots to the "metal pot" of a linotype machine or the like. In such a machine the metal pot is kept heated to maintain the type metal in a molten state and as the metal is used up for casting the type it must be replenished by hand as needed. In order to relieve the operator of the duty of constant vigilance required to keep the pot properly charged, and of manually feeding fresh ingots of metal to the pot I have provided automatic means which will add new ingot bars to the pot as often as is necessary, said means being controlled by float means governed by the level of the molten metal in the pot.

Among the other objects of this invention, I have sought to provide a device which is attractive, efficient, convenient, and satisfactory for use wherever found applicable.

Many other objects and advantages of the construction herein shown and described, will be obvious to those skilled in the art from the disclosure herein given.

To this end my invention consists in the novel construction, arrangement and combination of parts herein shown and described and more particularly pointed out in the claims.

In the drawings, wherein like reference characters indicate like or corresponding parts;

Figure 1 is a top plan view of my device as viewed from above;

Figure 2 is a side elevation of the same;

Figure 3 is a section taken substantially on the line 3—3 of Figure 1;

Figure 4 is a section taken substantially on the line 4—4 of Figure 3;

Figure 5 is a bottom plan view of my device with parts broken away;

Figure 6 is a section taken substantially on the line 6—6 of Figure 1;

Figure 7 is a section taken substantially on the line 7—7 of Figure 2;

Figure 8 is a section taken substantially on the line 8—8 of Figure 9;

Figure 9 is a section taken substantially on the line 9—9 of Figure 8;

Figure 10 is a section taken substantially on the line 10—10 of Figure 1;

Figure 11 is a section taken substantially on the line 11—11 of Figure 1;

Figure 12 is a fragmentary section of the trough showing filler insert blocks in place for a different length of ingot bar;

Figure 13 is a top plan view of a modified form of my device;

Figure 14 is a side elevation of the same; and

Figure 15 is a detail of the float-controlled operating arm therefor.

In the drawings, wherein I have shown a preferred embodiment of my invention, 1 represents a trough, preferably inclined so that the material placed thereon will be gravity actuated, and 2, represents the discharge end thereof, said discharge end preferably being detachably secured to said main section of the trough. The sides 3 and 4 of the trough extend laterally of the bottom and may be formed of angle-irons as shown, or may be formed in any other suitable or desired shape. Said discharge end 2 of the trough, as shown, is secured to the main section by means of a pair of locking arms 5, one at each side thereof and engageable with a cooperating slot formed in the sides of the main trough section 1 at its end adjacent the discharge section. If desired, a latch 6 may be secured to the discharge section 2, said latch being engageable with a pin 7 on the main trough section 1 in order to more securely position the parts together to prevent accidental displacement therebetween, (see Figure 2).

An opening 8 is formed in the discharge end 2, said opening having bounding walls 9, one of which, as for instance 10, is inclined downwardly and inwardly to the bottom thereof. The discharge opening 8 is positioned over the "metal pot" or crucible, 11, 100 of a linotype or the like machine, said crucible being adapted to contain molten metal therein, as for instance type metal. Adapted to be secured to the pot 11 is an abutment part 12, which as shown, (see Figure 6) is comprised of a pair of members adapted to be clamped together over the wall of the pot and to project thereabove, one of said members having its outer end bent angular of itself, as at 13, and having a recess or slot 14, 110

formed at the angle thereof for a purpose to be hereinafter described.

The trough is adapted to be secured to a stationary part 15 of the linotype machine 5 by a plurality of supports 16, said supports being any suitable shape and secured to said parts in any suitable or desired manner. The trough is adapted to receive a plurality 10 or a series of ingot bars 17 thereon, said bars being slidable on the trough and movable downwardly thereon under the force of gravity. Near the bottom end of the trough section 1, (see Figures 5, 6, and 7), is a pair of front stop members 18 and a rear stop 15 member 19, said members being vertically movable through apertures provided in the bottom wall of the trough. The lower end of each of said stop members 18 and 19 is pivoted to arms 20-21 respectively, said 20 arms being rigidly secured to a rock shaft 22 journaled at its ends in lugs 23 depending from the sides of the trough. To one end of the rock shaft is secured a lever arm 24, the free end of said lever arm being pivotally 25 connected to a link member 25, said link member being slidably connected at its other end to the end of a slide bar 27, said slide bar having an elongated slot or the like 26, provided therein. Said slide bar is 30 slidably mounted in guides 28 depending from the sides of the trough so as to be capable of reciprocating movement in said guides. Each of the guides is adjustable in a vertical plane so that the slide bar may be 35 raised or lowered as desired.

At the other end of the slide bar is arranged a hook 29 adapted to be engaged by the slotted portion 14 of the reciprocating pot abutment member 12, so that when said 40 hook is engaged by said abutment member the slide bar will be actuated thereby to operate said stop members. The hook 29 is pivotally mounted at 30 in the slide bar 27 and at its other end there is arranged a weight 45 31, so that the hook will normally lie in the position shown in full lines in Figure 8, there being abutment stops 32 and 33 respectively to limit the downward and upward movement of said hook bars, the downward movement of the hook being indicated in dotted lines.

Normally the hook is up, out of the path of movement of the abutment member 12 of the reciprocating pot 11, as shown in Figure 55 8, so that the slide bar will not be engaged by said member to operate the stop members. In order to position the hook in the path of the abutment member 12 at the proper time, in order to release the forward 60 stop mechanism, I have provided float-controlled means comprising a float member 33 adapted to be immersed in the molten metal within the pot, said float member being carried by a float-carrying arm 34 substantially of bell crank shape, said bell crank

being pivotally mounted at 36 upon the slide bar 27, the other arm 35 of the bell crank being adapted to engage a pivotally mounted link 37 pivoted at 38 on the slide bar. Said pivotally mounted link has a head or actuating end 39, said head being adapted to engage within a cut-away portion 40 of the hook bar 29. As shown in Figure 8 (the full line position showing the normal position of parts, or when the level of the liquid in the 70 pot is above its critical or predetermined level) a drop in the level of the liquid in the pot will cause the float to drop, carrying the bell crank arm 34 downwardly and raising its opposite end 35 to move the 75 pivotally mounted link 37 upwardly about its pivot so that its hook 39 engages the hook bar 29, moving it about its pivot 30 so as to position it downwardly and into the path of movement of the abutment member 12. Said abutment member 12 will engage the hook 80 as the pot reciprocates and will cause the slide bar 27 to be moved in the direction of movement of the pot, this movement being transmitted through the levers and links 85 25 and 24 to the stop members 18 and 19, such an outward movement of the slide bars lowering the front stops 18 below the carrying surface of the trough and raising the rear stop 19, whereby the end ingot is released and is allowed to move down the trough, fall into and through the discharge opening and into the mouth of the pot, the raised rear stop 19 preventing the downward movement or discharge of any of the 90 100 succeeding ingot bars.

A spring 40, (see Figure 2), having one end secured to the slide bar and another end to some stationary part, as for instance the guide bar 28, causes the slide bar to be retracted to its normal rearward position when the pull of the abutment member 12 is released from the hook 29 on the reverse movement of said abutment member. This retraction or backward movement of the slide bar causes the rear stop to be depressed and the forward stops to be raised again whereby the ingot bars may slide down the trough a distance equal to the width of one of the bars so that the new end ingot now 105 rests against the front stops and is in operative position to be discharged into the pot when the forward stops are again released by the pot. The discharge of the ingot bar into the pot raises the level of the liquid therein so that the float 33 no longer pulls on the arm 34 and as the hook arm 29 is weighted at its rear end the hook is returned into its normal inoperative position 110 out of the path of the abutment member 12 of the pot whereupon the spring 40 can act.

In order to prevent the ingot bars from tilting upwardly due to the weights of the rest of the ingot bars at their rear, I have provided a weight member 41 having a 115 120 125 130

central roller 42 or the like, said weight member being preferably U-shaped and having arms 43 pivotally mounted at their free ends to the sides of the trough, the 5 roller of said weight member normally bearing on the rear edge of the bottom ingot bar. In order to provide limiting stops for both the rise and fall of said weight member, I have adjustably secured to said arm 10 43 of the weight member, an angle-iron 44, (see Figures 3 and 4), one leg of which is positioned beneath the trough so that it engages said trough on its upward movement. Another stop member 45 is secured 15 to said trough adjacent the angle-iron 44 to limit it in its downward movement.

If desired, signal means may be provided 20 whereby the operator will be notified by said signal whenever the trough becomes empty, said signal means comprising a bell 46, or the like, mounted on the trough and having a clapper arm 47, said clapper arm being actuated by the end 48 of one of the 25 arms 43 whenever the roller 42 drops, due to there being no ingot passing beneath it. Of course, it is understood that said signal means may be either a bell, as shown, or any other suitable signal means, visible or 30 audible, and either mechanically or electrically operated.

In order to accommodate various lengths of ingot bars, I have formed apertures or 35 openings 49 in the bottom of the trough, said openings being adapted to receive dowel pins 50 of filler blocks 51, as shown in Figures 7 and 12. In this way, the ingot blocks may be of any size and will be prevented from tilting in the plane of the 40 through.

As has been previously pointed out, section 2 of the trough is removable so that access may be had to the pot for cleaning 45 purposes or the like whenever desired, simply by releasing the latch 6 and lifting the discharge end 2 out of its interlocking connection.

In the modification shown in Figures 13, 50 14 and 15, I have provided another form of rock shaft actuating means, whereby the stop members 18 and 19 may be actuated, said rock shaft 22 being secured at 53 to an arm 52. A float 54 is connected to said arm 52 at 55, said arm 52 being of any suitable 55 shape or structure, and, as shown, is made of three legs, rigidly connected together in a triangular formation, said legs comprising an upright 56, horizontal 57, and a connecting leg 58 between the free ends of said legs 56 and 57. In this modification the 60 stops are actuated by the drop and rise of the float, said arm 52 actuating the rock shaft 22 to accomplish said movement.

Having thus described my invention it is 65 obvious that various immaterial modifications may be made in the same without

departing from the spirit of my invention; hence I do not wish to be understood as limiting myself to the exact form, arrangement, construction and combination of parts herein shown and described or uses 70 mentioned.

What I claim as new and desire to secure by Letters Patent is:

1. In a device of the character described and in combination, a trough adapted to receive a plurality of ingots thereon, means for adjusting the inside width of said trough, means for temporarily maintaining the ingots in position on the trough, and means automatically operative for successively releasing the ingots. 75

2. In a device of the kind described and in combination, a trough adapted to receive a plurality of ingots thereon, stops controlling the discharge of said ingots therefrom, a weight member adapted to bear on said ingots to prevent the tilting thereof, and automatically operative float-controlled means independent of said weight member for actuating said stops to successively release said ingots. 80

3. In combination with a receptacle, a trough adapted to receive a plurality of ingots thereon, stops on said trough to limit the movement of said ingots thereon, a pivoted weight member adapted to bear on the ingot nearest the discharge end of said trough to prevent the tilting thereof, and automatically operative float-controlled means independent of said weight member and governed by the level of the liquid in 90 said receptacle for successively releasing said end ingots into said receptacle. 95

4. In combination, a trough adapted to receive a series of ingots thereon, front and rear stops for said ingots, a common rock shaft carrying and connecting both of said stops and float-controlled means for actuating said rock shaft and simultaneously raising one of said stops and lowering the other 100 to successively release said ingots. 105

5. In combination, a receptacle adapted to contain a liquid therein, a trough adapted to communicate therewith, and to receive a series of ingots slideable thereon, a forward and a rear stop at the front and rear sides of the end ingot closest the discharge end of said trough, a common rock shaft carrying and connecting said stops, float-controlled means governed by the liquid in said receptacle for actuating said rock shaft to simultaneously operate said stops to discharge said end ingots successively into said receptacle, and means for returning said float-controlled means to its normal position. 115

6. In combination, a reciprocatory receptacle adapted to contain a liquid therein, a trough having a discharge end in communication therewith and adapted to re- 120

ceive a series of ingots thereon, stop means at the forward side of the end ingot closest the discharge end, means operatively connected to said stop means to actuate it, float-controlled means controlled by the liquid in said receptacle for positioning said last mentioned means in the path of said receptacle whereby it may be engaged therewith and actuated thereby, and spring means for retracting said stop-operating mechanism when the level of said liquid is at its predetermined height.

7. In combination, a reciprocating receptacle adapted to contain liquid therein, an inclined trough having a discharge end in communication therewith and adapted to receive a plurality of ingots, stop means on said trough to the front and rear of the lowermost ingot for limiting the movement of the ingots on said trough, reciprocating means for operating said stops, and float-controlled means for positioning said reciprocating means so as to be directly engageable with the reciprocating receptacle and be operated thereby to release said lowermost ingot into said receptacle.

8. In combination, a reciprocating receptacle adapted to contain a liquid therein, a trough having a discharge end in communication therewith and adapted to receive a series of ingots thereon, means for releasing said ingots successively whereby they are discharged into said receptacle, said means comprising a float-controlled member governed by the liquid in said receptacle, a hook pivoted to said ingot releasing means and operable by said float member to position said hook in the path of said reciprocating

cating receptacle so that it may be engaged thereby to operate said ingot releasing means.

9. In combination, a reciprocating receptacle adapted to contain liquid therein, an inclined trough having its discharge end in communication therewith and adapted to receive a series of ingot bars thereon, stop means on said trough in advance of said ingots to prevent their free discharge into said receptacle, a reciprocatory member for operating said stop means, a hook on said reciprocating member, and float-controlled means operatively cooperating with said hook to position it in the path of said reciprocating receptacle so that it may be engaged thereby to reciprocate said reciprocatory stop operating mechanism and successively release the end ingots into said receptacle.

10. In combination with a reciprocating receptacle adapted to contain a liquid, an inclined trough having its discharge end in communication therewith and adapted to receive a series of ingot bars thereon, float-controlled means for releasing said ingot bars successively into said receptacle, a weight adapted to bear on the end ingot to prevent the vertical tilting thereof and independent of said ingot releasing means, and signal means operable by said weight when the last ingot moves past it.

In testimony whereof, I have hereunto signed my name in the presence of two subscribing witnesses.

HARRY KRAUTBLATT.
